J. R. Kellin Attorney

UNITED STATES PATENT OFFICE.

FRED PRACHT, OF WILLIAMSVILLE, MISSOURI.

WIRE FASTENER FOR FENCEPOSTS.

Application filed April 4, 1921. Serial No. 458,283.

To all whom it may concern:

Be it known that I, FRED PRACHT, a citizen of Germany, having declared my intentions to become a citizen of the United States, residing at Williamsville, in the county of Wayne and State of Missouri, have invented certain new and useful Improvements in Wire Fasteners for Fenceposts, of which the following is a specification.

This invention relates broadly to fence posts and more particularly to a fence post including improved means for retaining a wire fence in place in connection therewith.

The main and principal object of the invention is to provide a device of the above character which in addition to a fence post proper is provided with spaced openings, a hindgedly mounted retaining member so mounted that when in a fully closed position will be held in spaced relation to the adjacent side of the fence post and which carries retaining means adapted to project through the openings in the fence post whereby the retaining member will be securely held in position.

Various other objects and advantages of my invention will become apparent during the continuance of the following description.

In the drawings:—

Figure 1 is a view in front elevation showing my invention as in its preferred embodiment and as used in connection with a wire fence of conventional form.

Figure 2 is a view in side elevation showing parts in section and also showing the retaining member in open position in dotted line.

Figure 3 is a view in horizontal cross section taken on line 3—3 of Figure 2 looking downwardly in the direction indicated by the arrow.

In describing my invention more in detail, 10 indicates the fence post which is preferably formed of steel but which may be made of any other suitable or desirable material and which is mounted in a concrete block 11. Near its upper end the post is provided with a through opening 12 and about midway its ends with a second opening 13. The purpose of these openings will be hereinafter described.

A plate 14 of suitable length, width and thickness is secured to one side of the fence

post as at 15 and carries outstanding lugs or ears 16 that receive a pintle 17. It is pointed out that the thickness of the plate 14 is preferably the same thickness as the strands of wire which comprise the fence 18 so that while the retaining member which is carried by the posts may firmly engage the strands of wire as will be hereinafter described, it will be held in spaced relation to the adjacent base of the post 10 so as not to mash or cut the horizontal strand of wire which would otherwise be the case.

The retaining member 19 is in the form of a metallic bar which receives the pintle 17 at its lower end so that it will be held in pivotal relation to the fence post 10 as is obvious. At its upper end the retaining member 19 carries a bolt or similar fastening member 20 which is pivoted thereto as at 21 so that when the retaining member is moved into position shown in Figure 2, the bolt 20 passes through the opening 12 of the fence post. When the parts are in this position, a nut 22 may be screwed onto the free end of the bolt 20 so as to securely retain the bolt in place and as a result maintain the retaining member 19 in rigid relation with respect to the post. The retaining member 19 is further provided, intermediate its ends with an opening to receive a removable bolt 23 which when in place also passes through the opening 13 of the fence post and which may be securely fastened by means of a nut 24. In the operation of my invention the nuts 22 and 24 are unfastened which will allow the bolts 20 and 23 to be withdrawn from the openings 12 and 13 and thereby enable the operator to move the retaining member 19 into the position shown in dotted line in Figure 2. The wire fence is then engaged with the post 10 as shown in Figures 1 and 2 after which the retaining member 19 is moved back into its normal position and the bolts 20 and 23 pass through the openings 12 and 13 of the fence post.

After this has been done, the nuts 22 and 24 are screwed into place so as to maintain the retaining member 19 in a secure position with respect to the fence post and draw the same tightly against the horizontal strands of the fence 18. As above pointed out, while the retaining member 19 firmly engages the horizontal strands to the fence and securely retains the same in place, it is prevented from mashing or cutting the same by means of the plate 14.

14 whose thickness is substantially the same as the thickness of the wire strands which compose the fence.

From the above it will be observed that 5 the retaining member can be quickly and easily operated and that it can be associated with a fence post of conventional form without materially altering the construction thereof.

10 From the foregoing it is believed that the advantages and novel features of my invention will be readily understood and therefore further detailed description is deemed unnecessary.

15 What is claimed is:—

1. In a device of the character described the combination with a fence post provided with spaced openings, of a plate secured to one side of said fence post adjacent the bottom thereof, a retaining member pivotally mounted on said plate at a point spaced from the edges thereof, means carried by said retaining member adapted to pass through said openings in said fence post, 20 means to fasten said last mentioned means and thereby maintain said retaining member in rigid relation to said fence post, and said 25

plate being adapted to limit movement of said retaining member in one direction and maintain the same in spaced relation to said fence post substantially as described. 30

2. A wire fastener for fence posts comprising, in combination, a fence post provided with spaced vertically aligned openings, a plate disposed to lie flat against a side of the 35 post and secured thereto beyond the aligned openings, said plate provided with outstanding lugs arranged to project from an intermediate portion thereof, a retaining bar having one end pivotally connected to the 40 lugs of the said plate whereby the bar may be swung upwardly against the side of the post to over-lie the openings therein, said bar when in its upwardly swung position being held spaced from the post by a portion 45 of the plate lying between the bar and the post, and a securing member pivotally supported at the free end of the bar and passing in the upward position of the bar thru one of the openings in the post to provide for retaining the said bar in position. 50

In testimony whereof I affix my signature.

FRED PRACHT.
